United States Patent Office

Des. 195,198
Patented May 14, 1963

195,198

CEILING TILE

Wallace Lanz, New York, N.Y., assignor to Minnesota and Ontario Paper Company, Minneapolis, Minn.

Filed June 12, 1962, Ser. No. 70,513

Term of patent 14 years

(Cl. D18—2)

FIG. 1

The bottom of the tile is substantially plain.

I claim:

The ornamental design for the ceiling tile, substantially as shown and described.
